CLAIM

The ornamental design for a dispensing tube for liquid
or paste-like substances, as shown and described.

DESCRIPTION

FIG. 1 is a perspective view of a dispensing tube for
liquid or paste-like substances showing our new design;
FIG. 2 is a plan view;
FIG. 3 is a side view;

FIG. 4 is a view looking from the right of FIG. 3; and
FIG. 5 is a view looking from the left of FIG. 3.
